(57) **CLAIM**

We claim the ornamental design for an illuminated power box, as shown and described.

DESCRIPTION

FIG. 1 is a perspective view of an illuminated power box showing the new design.

FIG. 2 is a front elevation view of the illuminated power box shown in FIG. 1.

FIG. 3 is a left side elevation view of the illuminated power box shown in FIG. 1.

FIG. 4 is a right side elevation view of the illuminated power box shown in FIG. 1.

FIG. 5 is a top plan view of the illuminated power box shown in FIG. 1; and,

FIG. 6 is a bottom plan view of the illuminated power box shown in FIG. 1.

The broken lines illustrate portions of the illuminated power box that form no part of the claimed design.

1 Claim, 5 Drawing Sheets
